FOREIGN PATENT DOCUMENTS

CN 207082665 U * 3/2018 ..... H01R 13/46

Primary Examiner — Marie D. Fast Horse(74) *Attorney, Agent, or Firm* — McClure, Qualey & Rodack, LLP(57) **CLAIM**

The ornamental design for a terminal, as shown and described.

DESCRIPTION

FIG. 1 is a front perspective view of a terminal, in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The broken lines in the drawings depict portions of the terminal that form no part of the claimed design.

1 Claim, 7 Drawing Sheets(56)
